UNITED STATES PATENT OFFICE.

CARL B. ROEBKEN, OF WASHINGTON, DISTRICT OF COLUMBIA.

LIGHT-REFLECTING MEANS.

Application filed December 1, 1925. Serial No. 72,502.

My invention relates to the construction of lamps and is particularly adapted for use where an even and diffused lighting effect is desired, at the same time providing a 5 light having a long distance projection. When used in connection with motor vehicles, my improved head light will effectually eliminate the dreaded blinding effect ordinarily produced by high powered head 10 lights, thereby rendering night driving considerably safer.

My invention further provides means for not only regulating the beam of projection of the high powered lighting effects, but the 15 direction of projection may be readily adjusted so as to conform to the operator's wishes and to the regulations of particular jurisdictions. The scope of my invention extends to whatever construction may be defined by or included within the terms or language of the appended claims.

In the drawing:

Figure 1 is a central longitudinally sectional view illustrating my improved light 25 in connection with a hanging or drop light;

Figure 2 is a similar view showing the light in connection with a head light and

Figure 3 is a view in perspective of the inner casing or reflector holding means.

30 My invention, in the form or embodiment shown in the drawing and briefly described, comprises an outer shell or reflector, 10, an inner reflector, 11, means, 12, for adjustably supporting the inner reflector and lighting 35 means centrally located within the outer reflector and rearwardly of the inner reflector.

Referring particularly to Figure 1, the outer reflector, 10, is formed of a plurality of annularly disposed and outwardly curved 40 portions, 13, which are treated on their inner surfaces for the purpose of reflection, depending upon the quality or projection of light that is desired. I have found by actual experiments that when forming this outer reflector, 10, of aluminum, that a very desirable and highly efficient light is produced.

An exteriorly threaded socket, 14, is centrally located within the reflector, 10, and securely held in position by means of the 50 ring or similarly constructed member, 15, which may also be used for hanging the fixture. The electric bulb, 16, is, of course, mounted within the socket, 14, in the usual manner.

55 A relatively short distance below the bulb

or-electric light, 16, is adjustably mounted the inner reflector, 11, so that it may be either moved toward or from the light, 16, or it may be tilted. The supporting member, 12, is preferably formed, as is indicated in Figure 3, of a hub portion, 17, and a pair of downwardly extending and diametrically opposed arms, 18, and a similarly extending arm, 19.

The outer extremities of the arms, 18, are 65 provided with openings, 19', for the purpose of pivotally mounting the inner reflector, 11, as is clearly indicated in Figures 1 and 2, as at 20, whereas, the outer extremity of the arm, 19, is provided with a longitudinally extending slot, 21. In the form of my invention illustrated in Figure 1, a transversely extending arm, 22, is integrally formed upon the outer portion of the inner reflector, 11, for the purpose of receiving a screw, 23, 70 which is adapted to pass through the slot, 21, for locking the inner reflector, 11, in its adjusted position. It will be noted that the outer end of the arm, 19, is curved conforming to an arc, with the pivotal point, 20, 75 as its center, thereby providing a uniform bearing surface along the entire distance of the slot, 21. The opening, 24, of the hub portion, 17, is preferably made slightly larger than the outer diameter of the threaded portion, 14, of the socket to permit its ready adjustability. Lock nuts, 25, are adapted to engage this threaded portion, 14, for securely locking the supporting member, 12, in its 80 adjusted position.

The inner reflector, 11, is preferably constructed of relatively thin sheet metal, having two or more outwardly bulging and annularly disposed ring portions. In this instance, the outer surface of the inner reflector, 11, is polished or otherwise treated for reflecting the rays of light from the bulb, 16, rearwardly against the curved surfaces, 13, of the outer reflector, 10, from which points they are again reflected forwardly, as indicated diametrically in Figure 2.

A lens, 25', is mounted within the enlarged end of the inner reflector, 11, for purposes of projection. This is particularly advantageous for use in connection with head lights wherein it is often desirable to penetrate fogs and other heavy atmospheres upon certain portions or angles of the road bed.

110 In Figure 2, a slightly different form of

arm, 19, is illustrated and for the purpose of ready adjustment, the screw threaded pin, 26, is mounted upon the outer rim, 27, of the inner reflector, 11.

5 I claim:—

1. A lighting structure including an outer reflector, a socket arranged centrally within the outer reflector, a light source in said socket, an inner reflector arranged within 10 the outer reflector and in advance of the light source, said inner reflector being formed with an opening to permit the passage of light rays through the inner reflector, a lens carried by the inner reflector, and means for 15 supporting the inner reflector from said socket and movable longitudinally of said socket to permit the adjustment of the inner reflector to and from the light source, said means including a pivotal support for the 20 inner reflector to permit a tilting thereof on an axis fixed in the plane of the lens and

an element for fixing the inner reflector in tilting adjustment.

2. A lighting structure including an outer reflector, a socket arranged centrally within the outer reflector, a light source in said socket, an inner reflector arranged within the outer reflector and in advance of the light source, said inner reflector being formed with an opening to permit the passage of 25 light rays through the inner reflector, a lens carried by the inner reflector, a support for the inner reflector, including a hub portion for adjustable mounting on said socket, arms projecting from the hub for pivotally engaging the inner reflector at diametric points to permit tilting of the inner reflector, a third arm projecting from the hub, and means for adjustably fixing the inner reflector to such third arm for securing the 30 inner reflector in desired tilting adjustment.

CARL B. ROEBKEN.
